UNITED STATES PATENT OFFICE.

ALFRED B. FOWLER, OF BEVERLY, MASSACHUSETTS, ASSIGNOR TO UNITED SHOE MACHINERY COMPANY, OF PATERSON, NEW JERSEY, A CORPORATION OF NEW JERSEY.

CHANNEL-GUIDE MECHANISM FOR SEWING-MACHINES.

1,226,070.

Specification of Letters Patent. Patented May 15, 1917.

Application filed July 24, 1915. Serial No. 41,675.

To all whom it may concern:

Be it known that I, ALFRED B. FOWLER, a citizen of the United States, residing at Beverly, in the county of Essex and State of Massachusetts, have invented certain new and useful Improvements in Channel-Guide Mechanism for Sewing-Machines; and I do hereby declare the following to be a full, clear, and exact description of the invention, 10 such as will enable others skilled in the art to which it appertains to make and use the same.

The present invention relates to inseam shoe sewing machines and more particularly to channel guide mechanism employed in connection with such machines.

Inseam sewing machines of the usual type are provided with a channel guide engaging in the channel of the shoe and a coöperating feed point or awl also engaging in the channel. Both the channel guide and feed point are moved toward and from the work and are mounted upon a common feed slide which imparts a lateral movement in the 20 line of feed to both members. The channel guide is ordinarily supported upon the opposite side of the feed point from the needle and when in contact with the shoe occupies a considerable space which may interfere 25 with the manipulation of the shoe, particularly when sewing about the toe.

The object of the present invention is to provide an improved form of channel guide mechanism which overcomes the difficulties heretofore experienced in sewing about the toes of shoes, and which retains the shoe in the proper operative position during the feeding movement. With this object in view a feature of the invention contemplates 30 the provision of a cam operated channel guide movable transversely to the direction of feed to engage and release the work during each cycle of operations, and a spring acting in advance of the cam for moving the guide yieldingly into engagement with the work.

In the accompanying drawings illustrating the preferred form of the invention; Figure 1 is a side elevation of an inseam shoe sewing machine embodying the present invention; Fig. 2 is a detail showing a portion of the channel guide actuating mechanism; and Figs. 3, 4, 5 and 6 are diagrammatical views illustrating the relative posi-

tions of the feed point and channel guide at 55 different points in the operation of the machine.

The machine shown in the illustrated embodiment of the invention, except as herein-after described, is essentially the same in 60 construction and mode of operation as the shoe sewing machine disclosed in the patent to Eppler, No. 1,108,560, dated August 25, 1914 and in consequence will not be described in detail herein.

The machine illustrated in Fig. 1 comprises the usual curved hook needle 1 actuated through a lever 2 and a link 3, and a curved awl 4 fulcrumed at 5 and engaging on the opposite side of the work from the 70 needle. The machine is also provided with a back rest 6, a channel guide 7 engaging in the channel of the shoe upon the opposite side from the back rest, and a thread looper 8 operating in the usual manner. Both the 75 channel guide and feed point are mounted upon a feed slide 10 slidably supported upon parallel guiding studs 12 and actuated by a lever 14 fulcrumed between its ends at 15 and operatively connected at its rear end 80 to a rotary cam disk. The channel guide 7 is adjustably supported upon a channel guide lever 16 fulcrumed upon the feed slide at 18 and operatively connected at its upper end to a channel guide actuating lever 85 20 pivoted upon the machine frame at 21. The operative connection between the lever 20 and the channel guide lever 16 conveniently comprises a tooth 22 formed upon the lower end of the lever 20 and meshing 90 with a corresponding tooth 23 formed upon the upper portion of the channel guide lever 16. The rear end of the lever 20 is operatively connected with a suitable cam path formed in the face of a cam disk 24.

It is desirable that the channel guide shall engage with the work and retain the work in the proper operative position during the feeding movement, but it is furthermore desirable that this engagement of the 100 channel guide with the shoe shall not interfere with the substantially free manipulation of the shoe when passing about the toe. To this end the present invention contemplates the provision of a spring arranged to cause the channel guide to initially engage the work with a yielding pressure and a cam for finally actuating

the guide to complete the work engaging movement of the guide when at the end of its feed movement. Upon referring to Figs. 1 and 2 of the drawings it will be noted that the channel guide lever 16 is operatively connected with a spring 35 interposed between the feed slide and a recess 36 formed in the lever and normally tending to rock the lever in a direction to cause a movement of the channel guide toward the channel of the shoe. The spring 35 is retained in position by a stud 38 secured in the channel guide lever and passing loosely through the feed slide, as shown clearly in the drawings. In order to permit the operation of the channel guide at predetermined intervals by the spring it will be noted that a portion 40 of the channel guide actuating cam is cut away to permit a movement of the channel guide independently of the cam.

The relative movements of the awl and channel guide will be clearly understood from an inspection of Figs. 3, 4, 5 and 6 in which 28 indicates the between substance of an insole of a lasted shoe, 29 the upper, and 30 the welt. For the sake of clearness the seam of chain stitches which are formed during the operation of the machine has been omitted and the holes made successively in the work by the action of the awl and needle are indicated at 31. Fig. 3 illustrates the position of the feed point and channel guide at the end of the backward or idle movement of the feed slide. While the feed slide remains at rest the awl and channel guide are moved toward the work, the point of the awl piercing the between substance of the insole and the insole channel guide yieldingly engaging in the channel through the action of the spring 35. The feed slide is now actuated to cause the feed point to feed the work and during this movement of the slide the channel guide moves with the work and continues to engage the channel with a yielding pressure. At substantially the completion of the feeding movement the channel guide is caused to positively engage in the channel of the shoe through the cam and actuating lever 20. The awl and channel guide are

finally retracted as indicated in Fig. 6 and returned by the backward movement of the feed slide to the initial position, indicated in Fig. 3. While the awl and channel guide are in the position shown in Fig. 5 the needle advances toward the work and as it passes through the work the awl is retracted. The channel guide, however, is caused to positively engage with the channel during the passage of the needle through the work and supports the work against the thrust of the needle. With this construction it will be obvious that the channel guide acts effectively to support and guide the work during the feeding and sewing operation and at the same time permits the proper manipulation of the shoe in sewing about sharp curves.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. An inseam shoe sewing machine, having in combination, stitch forming devices, a channel guide movable transversely to the direction of feed to engage and release the work during each cycle of operations, a cam for positively moving the guide in both directions, and a spring acting in advance of the cam for moving the guide yieldingly into engagement with the work. 80

2. An inseam shoe sewing machine, having in combination, stitch forming devices, a channel guide movable transversely to the direction of feed to engage and release the work and movable in the direction of feed during each cycle of operations, a cam for positively moving the guide in both directions acting to complete the work engaging movement when the guide is at the end of its feed movement, and a spring acting in advance of the cam for moving the guide yieldingly into engagement with the work. 90

ALFRED B. FOWLER.
